UNITED STATES PATENT OFFICE.

EDWARD C. SWEETMAN, OF TOLEDO, OHIO.

TRAFFIC-CONTROL APPARATUS.

Original application filed February 4, 1927, Serial No. 165,795. Divided and this application filed March 18, 1928. Serial No. 262,138.

This invention relates to traffic control devices employed at street intersections for automatically directing traffic along such streets, but more particularly to apparatuses or switches which are recurrently operable to energize the traffic signals. This application constitutes a division of my application Serial No. 165,795, filed February 4th, 1927.

An object of this invention is to provide a simple and efficient traffic control apparatus for recurrently energizing traffic signals, which is so constructed that a plurality of street intersections may be automatically operated from a single operating unit without mercury switches or devices of similar nature, which empirically have been found to be objectionable for continuous operation.

Another object of the invention is to provide a traffic control apparatus for controlling traffic signals in a plurality of intersections having new and improved features of construction to enable the timing of the signals to be readily and conveniently varied at will without stopping the operation of the apparatus.

Other objects will hereinafter appear.

In order that the invention may be fully understood, description is given of a system to which my control apparatus is admirably adapted, the system forming the subject matter of my co-pending application above referred to. Accordingly, for purposes of illustration and not of limitation, the invention is shown in the accompanying drawings, in which:

Fig. 1 is a diagrammatic view of the wiring for the traffic control system to illustrate the operation;

Fig. 2 is a vertical sectional view of the casing for the operating mechanism of the traffic control apparatus showing the parts in elevation;

Fig. 3 is a vertical sectional elevation of the casing showing the front view of the traffic control apparatus;

Fig. 4 is an enlarged vertical sectional elevation of the piston and cylinders;

Fig. 5 is a top view of the cylinder showing the adjusting handle for regulating the timing of the traffic signals;

Fig. 6 is a transverse section on the line 6-6 of Fig. 4; and

Fig. 7 is a fragmentary sectional elevation of an alternating form of conductor for engaging the contact elements.

In the embodiment of the invention shown on the drawings, lamps are used for signals, there being red lamps for stopping traffic, green lamps for moving traffic and amber lamps for continuing traffic, the latter being displayed between the green and red lamps, and these lamps being designated by the letters "R", "A" and "G". On the drawings are indicated signals on two streets for controlling traffic lengthwise, and crosswise of the drawing, and these signals are positioned at the street intersections, as will be understood. The signals are arranged in groups A, B, C, and D at the respective street intersections, and each group is composed of two sets of signal lamps, one set for controlling crosswise traffic, and the other for controlling lengthwise traffic, it being apparent that when the green lamps of one set are lighted the red lamps of the other set are lighted, and that between changes from red to green, the amber lights of both sets are lighted.

As shown, the groups A and B are connected in parallel and may be continued at length. Also the groups D and C are connected in parallel and then as many additional groups as desired may be added. The leads from groups A and B are joined to connecting leads to which the leads from groups C and D are similarly connected. The connections in parallel between adjacent groups will be readily understood from an inspection of Fig. 1, and need not be described in detail, and the groups A and C are joined in a similar manner to the connecting leads so that detailed description of the group A and its leads is deemed sufficient.

The group A consists of two sets of signal devices, the set *a* for controlling traffic lengthwise of the drawing, and this set *b* for controlling traffic crosswise of the drawing. As shown, each signal device consists of a red, amber and green lamp, which are connected to main leads 1, 2 and 3.

The red lamps of the set *a* are connected to the leads 3 by leads 4, the amber lamps being connected to the lead 2 by leads 5, and the green lamps to the lead 1 by leads 6. Similar sets of signal devices of the group B are similarly joined to main operating leads, 1, 2 and 3, and it will be apparent that these leads may be extended to any suitable length with as many groups of signal devices as desired joined thereto.

The red lamps of the set *b* are joined to

the lead 1 by leads 7, the amber lamps being connected to the lead 2 by leads 8, and the green lamps to the lead 3 by leads 9. From the above connections, it is manifest that the 5 amber lamps of both sets are joined to the lead 2, but the green lamps of the set *a* are connected to the lead 1 while the green lamps of the set *b* are connected to the lead 3. The red lamps of the set *a* are joined to the lead 10 3, but the red lamps of the set *b* are joined to the lead 1.

The main operating leads 1, 2 and 3 are separated to accommodate a blade switch 10 so that the normal operation of the signals of 15 the groups A and B may be interrupted at will, and the ends of these leads are joined to connecting leads 11, 12 and 13 respectively.

From the description so far, it is apparent when current is supplied to the connecting 20 lead 11 the green lamps of set *a* and the red lamps of set *b* are concomitantly lighted in groups A, B, C, and D, and also when current is supplied to the connecting lead 12, the amber lamps in both sets *a* and *b* are lighted. 25 Further, when the connecting lead 13 is energized, the red lamps of set *a* and green lamps of set *b* are simultaneously lighted in all groups of signals. Grounds for the various signal elements are indicated on the 30 drawing by dotted lines terminating in an element 13^a, and need not be described in detail. The switch 10 of either system may be manipulated to disconnect either or both systems from the connecting leads 11, 12 and 35 13. It will be evident that when a switch 10 is thrown out, the respective system is disconnected, although the remaining systems are operatively connected to the connecting leads and may normally operate in an independent manner.

The connecting lead 11 is connected to contact strips 14, 14^a and 14^b by a power lead 40 15; the lead 12 being connected to strips 16, 16^a and 16^b by a power lead 17; and the lead 13 being connected to contact strips 18, 18^a and 18^b by a power lead 19. The power leads 15, 17 and 19 are interrupted by a switch 20 which may be manipulated 45 to disconnect all systems from the power source.

Current is supplied in well known manner to an element 21 which thru suitable instrumentalities may be successively and recurrently brought into contact with one set 50 of strips 14, 16 and 18; 14^a, 16^a, and 18^a; or 14^b, 16^b and 18^b and thereby positively and concomitantly energize the signal devices. It is to be noted that the upper and lower contact strips are of different lengths and this is 55 to enable the period during which the various signal elements are displayed to be varied. If the movable contact element travels over the contact strips 14, 16 and 18, the green lamps of the sets *a* and red lamps of the sets 60 *b* will be displayed for a longer period of

time than the red lamps of the sets *a* and green lamps of the sets *b* which are controlled by the contact strip 18. The contact strip 16 controls the amber lamps as above mentioned.

The strips 14^a and 18^a are of substantially the same length so that the signals controlled thereby are displayed for periods of the same duration. The strip 14^b being shorter than the strip 18^b, the result is the 70 reverse of that described in connection with the strips 14, 16 and 18. It is usually desirable to display the amber lights for the same period of time so no variation in the length of the contact strips is shown on the 80 drawing.

The instrumentality which reciprocates over the contact strips and transmits energy from the element 21 controls the operation of all signals, and as above pointed out the 85 interval during which the red and green lights are displayed, may be varied at will. It is further apparent by the switches 10, one system may be disconnected from the power source and the remainder operate 90 normally and further that all systems may be thrown out by the switch 20 without the necessity of stopping or disconnecting the reciprocatory control instrumentality.

In emergency cases, as in the event of fire, 95 it is desirable to stop all traffic along certain streets and cross streets. In accordance with my invention, traffic on certain streets may be stopped without disturbing the normal operation of signals along other streets. 100 For this purpose, a power lead 22 extends from the live or power element 21, and is joined at its opposite end to a connecting lead 23 from which extend leads to the signal groups A, B, C and D, it being deemed 105 sufficient to describe the connection to the group A.

For the group A, an operating lead 24 branches from the connecting lead 23, and is interrupted or broken by the switch 10. The operating lead 24 serves both groups A and B and may be continued at length. Branching from the operating lead 24 are leads 25 which are operatively connected to the red lamps of the sets *b*; branch leads 26 from the operating lead 24 extend to the red lamps of the sets *a*. By throwing the switch 10 upwardly in Fig. 1, the red lamp of both groups A and B are lighted, and traffic at 115 these intersections stopped. Such operation does not in any way affect the normal operation of the signals in groups C and D, but a switch is provided so that all red lamps of these groups may be lighted independently of the groups A and B.

There are occasions when it is necessary to stop all traffic in a certain community or district, and with my traffic control system this may be readily accomplished. Branching from the power lead 22 is a lead 27 in- 120 125 130

terrupted by the switch 20, and connected to a connecting lead 28 from which extends a branch lead 29 joining the operating lead 24 in the manner shown. It will be understood that a similar connection for the groups C and D is provided, and for sake of brevity and clearness, description is given only in connection with groups A and B.

By moving the switch 20 upwardly in Fig. 1, red lamps of all groups are simultaneously lighted. It is evident that this may be effected without stopping or otherwise disturbing the operation of reciprocatory or interrupting instrumentality for currently engaging the contact strips. Manipulation of the switch 20 may be independent of the switches 10.

It will be observed that I have provided a traffic control system utilizing a single control unit at a central station. This obviates the necessity of using mercury relays which are well known to be sensitive to temperature changes, and therefore impractical. I have produced an arrangement whereby all stopping signals may be concomitantly displayed independent of the remainder, which may continue their normal operation.

It is to be definitely understood that although I have described my invention in connection with different colored lamps, other signal devices may be used to advantage, and I do not intend the invention to be limited to the use of lamps. Furthermore, although I have shown a wiring system which is practical, numerous changes may be made without departing from the spirit of the invention, the showing on the drawing being by way of illustration and not of limitation.

For controlling the operation of the signal elements, I provide operating mechanism disposed within a housing 30 having a switch box 31.

Positioned within the housing 30 on a shelf 32 is an electric motor 33, which is connected through suitable gear reduction 34 and pinion 35 to a gear 36 on a horizontal shaft 37. Fixed to the outer end of the shaft 37 is a disc 38 having a crank 39 to which is pivoted a depending rod 40. The lower end of the rod 40 is connected by universal joint to a slide 41, which is vertically reciprocatory in guides 42, depending from the shelf 32.

Connected to the slide 41 for vertical reciprocatory movements therewith is a tubular rod 43 which is movable in a tubular bracket 44 suitably fixed to the lower end of the guide 42. The connection between the tubular rod 43 and slide 41 is such to permit turning movements of the rod relatively to the slide.

Pivottally connected to the lower end of the tubular rod 43 is a piston rod 45 which is electrically insulated from the rod 43 by

a sleeve 46 of suitable insulating material, the pin 47 connecting these parts being also insulated from the rod 43 by bushings 48 of suitable insulating material. The piston rod 45 is of electrical conducting material and carries at its lower end a head 49 having transverse openings 50 therethrough.

The head 49 is reciprocable within a cylinder 51, which may be filled with oil or other suitable liquid in order to prevent arcing and provide a uniform movement to the head, the opening 50 through the head enabling the liquid to flow from one side to the other after the manner of a dash pot. Fitting within the cylinder 51 is a sleeve 52 of bakelite or other suitable electrical insulating material, and formed in the sleeve are longitudinal grooves 53, 54 and 55. Arranged within the grooves 53, 54 and 55 are contact strips. Within the groove 53 are the strips 14, 16 and 18; within the groove 54 are the strips 14^a, 16^a and 18^a; and within the groove 55 are the contact strips 14^b, 16^b and 18^b.

As shown in Fig. 6, binding posts 56 insulated from the casing in a suitable manner extend outwardly from each contact strip and leads attached to the binding posts are arranged in a manner hereinbefore described.

For engagement with the contact strips in the cylinder is an arcuately shaped strip 57 from which extends a pin 58, which engages the piston rod 45 at its inner end. In order to compensate for wear and hold the plate 57 outwardly in contact with the adjacent contact strip, a coiled spring 59 encircles the pin 57.

From the above description it will be manifest that rotation of the disk 38 through the connections described reciprocates the piston rod 45 and moves the arcuately-shaped contact strip 57 successively into engagement with a set of contact strips in the cylinder. It is to be noted that the strip 57, pin 58, piston rod 45 are of conducting material. The piston rod 45 is guided in a bushing 60 of conducting material, the bushing 60 fitting into a head 61 of non-conducting material. Extending outwardly from the bushing 60 is a binding post 62 to which live current is supplied from any suitable source. The binding post 62 corresponds to the live element 21 heretofore described. Current passes through the binding post 62, bushings 60, piston rod 45, pin 58, strip 57, contact strip engaged by the strip 57, and out through a binding post 56.

It will be noted that the contact strips secured to the insulating sleeve 52 are of different lengths, the purpose of this being heretofore pointed out. In order that the strip 57 may selectively engage the set of contact strips in the insulating sleeve desired by the operator, a handle 63 is pivotally con-

nected to a collar 64 fixed to the tubular shaft 43. The handle 63 may be turned horizontally in one direction or the other, and consequently the contact strip 57 on the piston head may be moved into position to engage one set of contact strips or another in the insulating sleeve 52 of the cylinder.

Formed on a bracket 65 adjacent the handle 63 are sockets 66, 67 and 68, corresponding to the three sets of contact strips in the insulating sleeve 52. This enables the operator readily to move the handle 63 to the proper position, and by placing the handle in one of the sockets, it will be held in the 15 adjusted position.

In the alternate form shown in Fig. 7, the head 49^a is provided with a plunger 69, the inner end of which is movable in an opening 70 formed in the piston rod 45^a. The plunger 69 is of conducting material, and is adapted to transmit current to the rod 45^a. The plunger 69 is urged outwardly by a coil spring 71 into engagement with a copper ball 72, which is adapted to engage the contact strips. The outer end of the plunger 69 is curved to fit the ball. In reciprocation of the head 49^a it is apparent that the ball 72 is yieldingly held in engagement with the contact strips, and is adapted to roll 25 thereover so as to reduce the friction between the head and contact strips and facilitate the movement of the plunger. Current passes through the ball 72 to the plunger 69, and from the plunger to the rod 45^a, as will be 30 apparent.

While the form of mechanism here shown and described is admirably adapted to fulfill the objects primarily stated, it is to be understood that it is not intended to confine 40 the invention to the forms of the embodiment herein disclosed, and it is susceptible of embodiment in various forms, all coming within the scope of the claims which follow.

45 What I claim as new and desire to secure by Letters Patent is:

1. A traffic control apparatus comprising a pair of relatively movable members, a plurality of annularly arranged rows of contact elements on one member, each row consisting of a plurality of contact parts of unequal length, a part on the other member movable into selective engagement with said rows, manual means to move said part into 55 engagement with a predetermined row, and power means to impart relative reciprocatory movement to said members.

2. A traffic control apparatus comprising a pair of relatively movable members, a 60 plurality of annularly arranged rows of contact elements on one member, each row consisting of a plurality of contact parts of unequal length, a pair on the other member movable into selective engagement with said 65 rows, lever means to move said part into

engagement with a predetermined row, and power means to impart relative reciprocatory movement to said members.

3. A traffic control apparatus comprising a cylinder, a reciprocable piston in said cylinder, a part of conducting material carried by and movable with said piston, a set of contact elements in said cylinder, said elements being of different lengths and arranged to be successively engaged by said 70 part during relative reciprocatory movement of the cylinder and piston, another set of contact elements of different construction than said first set, and means to move said part into engagement with one set or the other and being operable during reciprocatory movement of said piston, and means for reciprocating said piston.

4. A traffic control apparatus comprising a cylinder, a reciprocable piston in said cylinder, a part of conducting material carried by and movable with said piston, a set of contact elements in said cylinder, said elements being of different lengths and arranged to be successively engaged by said 85 part during relative reciprocatory movement of the cylinder and piston, another set of contact elements of different construction than said first set, and means for turning said piston to cause said part to engage 90 one set or the other and being operable during reciprocatory movement of said piston, and means for reciprocating said piston.

5. A traffic control apparatus comprising a pair of relatively reciprocatory members, 100 a set of longitudinally arranged contact elements of different lengths on one member, another set of contact elements of similar number but differently arranged from the first set, a part of electrical conductive material on the other member engageable with either set and adapted to be move successively into engagement with the contact elements of the respective set, means to shift said part to engage one set or the other, and 105 means to impart relative reciprocatory movement to said members.

6. A traffic control apparatus comprising a dash pot having a cylinder and piston reciprocable therein and liquid in the cylinder, 115 crank means to reciprocate said piston, a plurality of sets of contact elements in said cylinder, said sets consisting of contact elements of different lengths and the elements of one set being arranged differently from the elements of the other sets, a part of electrical conductive material on said piston engageable successively with the contact elements of one of the sets, and means to shift said part to one position or another for engaging a predetermined set, said means being operable during the reciprocatory movement of said piston.

7. A traffic control apparatus comprising an operating unit consisting of a part hav- 120

ing sets of contact strips, a conductor engageable with said contact strips, and means for adjusting the position of said conductor for engaging a predetermined set.

5 8. A traffic control apparatus comprising an operating unit consisting of a stationary cylinder having sets of longitudinally disposed contact strips of different lengths, a

plunger movable in said cylinder provided with a conductor engageable successively with said strips, and means for shifting said plunger to position said conductor for engaging different strips.

In testimony whereof I have hereunto signed my name to this specification.

EDWARD C. SWEETMAN.
